[57] CLAIM

The ornamental design for a revetment link block, as shown and described.

DESCRIPTION

FIG. 1 is a perspective view of a revetment link block embodying my invention, taken from an upper corner thereof;

FIG. 2 is a top view of the revetment link block of FIG. 1;

FIG. 3 is a typical elevational side view of the revetment link block of FIG. 1;

FIG. 4 is a typical elevational end view of the revetment link block of FIG. 1; and

FIG. 5 is a bottom view of the revetment link block of FIG. 1.
